[57] **CLAIM**

The ornamental design of a decal patch antenna system, as shown and described.

DESCRIPTION

FIG. 1 is a perspective view of a decal patch antenna system showing my new design;

FIG. 2 is a top view thereof;

FIG. 3 is a bottom view thereof;

FIG. 4 is an edge view thereof, the opposite edge view being a mirror image;

FIG. 5 is an end view thereof; and,

FIG. 6 is a view of the opposite end thereof.

The broken line in FIG. 1 illustrating a wire is for illustrative purposes only and forms no part of the claimed design.
